UNITED STATES PATENT OFFICE.

LEROY V. BERKEBILE, OF KANTNER, PENNSYLVANIA.

CARBURETER.

1,314,942.

Specification of Letters Patent.

Patented Sept. 2, 1919.

Application filed May 10, 1916. Serial No. 96,683.

To all whom it may concern:

Be it known that I, LEROY V. BERKEBILE, a citizen of the United States, residing at Kantner, in the county of Somerset and 5 State of Pennsylvania, have invented certain new and useful Improvements in Carbureters, of which the following is a specification.

My invention relates to new and useful 10 improvements in gas forming devices for carbureters, the primary object of my invention being the provision of a carbureter particularly adapted for use with low grade fuel, such as kerosene and heavy distillates 15 which will be economical in the use of fuel and which will insure flexibility of engine operation.

A still further object of my invention is the provision of a carbureter of the above 20 described character in which the liquid fuel is converted into a gas prior to its admixture with air, the gaseous fuel meeting the air just prior to its entrance into the engine manifold.

25 Heretofore, to the best of my knowledge, carbureters for use with kerosene and heavy distillate fuels have formed a moist or saturated vapor which, unless the air supplied was very hot, would condense even before 30 it reached the combustion chambers of the engine, with the result that a considerable quantity of the fuel was not burnt at all or was burnt so slowly as to give but a small percentage of the power which the 35 quantity of fuel used should create. My invention, by converting the fuel into a relatively dry gas and mixing it with the air, only just prior to its admission to the manifold, does away with all condensation 40 of the fuel and insures a perfect and rapid combustion of the entire mixture entering the engine cylinders thus greatly increasing the power of the engine and thus doing away with carbon deposits in the engine cylinders.

45 Another object of my invention is the provision of a carbureter which will cause the engine to operate with equal efficiency, as regards the quantity of fuel used, no matter what the rate of speed at which the 50 engine is running may be. Most carbureters, now in use, have a fuel feed which is dependent upon either air suction or pressure of the generated vapor, with the result that when the engine is running at less than its 55 maximum rate of speed, which is the great

majority of the time, an excess of fuel will be used as the mixture will be relatively rich. In other words, an engine, with the ordinary form of carbureter may run at its full efficiency only when running at its 60 maximum rate of speed. My invention aims to do away with this difficulty by having the fuel supply controlling mechanism entirely independent of air suction or vapor pressure. As a result, the engine operator 65 is furnished an engine having flexibility almost equaling that given to the operator of a steam engine and all unnecessary use of fuel is prevented.

More specifically, the main object of my 70 invention consists in the provision of a carbureter having a gas generating chamber into which the liquid fuel is fed and from which the gas generated is passed directly into the outlet passage of the carbureter, 75 being mixed with the air in this passage and in the manifold while on its way to the engine cylinders. In this connection, a further object of my invention consists in providing means whereby opening of the 80 throttle valve controlling supply of fuel of the engine controls the rate at which fuel shall be fed to the gas generating chamber of the carbureter.

Another object of my invention consists 85 in providing a carbureter having the above described fuel supplying means in which the air supply is automatic, being dependent upon the suction of the engine and, consequently, varying with the engine speed. In 90 this connection, another object of my invention consists in the provision of an adjustable valve by means of which the amount of air supplied to the engine at any given speed may be regulated.

95 A still further object of my invention consists in the provision of an efficient means for converting the liquid fuel fed into the gas generating chamber into a relatively dry gas which, when mixed with air, will 100 form a perfect explosive mixture.

With these and other objects in view, my invention will be more fully described, illustrated in the accompanying drawings, and then specifically pointed out in the claims 105 which are attached to and form a part of this application.

In the drawings:

Figure 1 is a perspective view of my improved carbureter;

Fig. 2 is a vertical sectional view taken axially of the gas generating chamber and float chamber;

Fig. 3 is a vertical sectional view taken axially of the gas generating chamber and at right angles to the view shown in Fig. 2;

Fig. 4 is a perspective view of the throttle valve;

Fig. 5 is a perspective view of the throttle valve lever and the cam carried by it which controls the rate of feed of liquid fuel to the gas generating chamber;

Fig. 6 is a central vertical sectional view of a modified form of heater for converting fuel fed to the gas generating chamber into gas;

Fig. 7 is a corresponding view of a still further modified form of heater.

Corresponding and like parts are referred to in the following description and indicated in all the views of the drawings by the same reference characters.

The carburetor illustrated in the drawings indicates a type for use upon smaller internal combustion engines, such as those commonly employed upon motor vehicles and I wish it understood that I do not intend to limit myself to any specific type, shape or proportion of parts, reserving the right to make any changes within the scope of the appended claims, without in the slightest degree departing from the spirit of my invention.

Broadly speaking, my carburetor includes a vertically disposed hollow cylindrical body 10 formed adjacent its upper end and at one side with a lateral cylindrical enlargement or casing 11 providing a float chamber 12 and this body 10 and enlargement 11 are disposed tangentially with respect to each other and are preferably connected by an integrally formed web 13. The float chamber, which is open at its upper end, is provided with a removable cover plate or closure 14 which may be secured to the wall of the float chamber by screws or bolts 15 and which is formed centrally with an opening to receive a hollow cylindrical valve chamber 17 having a valve seat 16. Fuel is supplied to this valve chamber through a laterally directed nipple 18 threaded for connection to a fuel supply pipe. The cover plate 14 is further formed with a vent opening 19 to relieve air pressure within the float chamber, admission of foreign matter through this opening being prevented by a perforated cap or strainer 20 closing the opening. The bottom wall of the casing 11 forming the float chamber 12 is provided with an upstanding socketed boss 21 which forms a lower guide for the stem 22 of the float valve 23, the opposite end of the stem 22 projecting into the valve chamber 17 and being guided by the valve seat 16. A float 24, of any suitable type,

is adjustably mounted upon the stem 22 of the float valve and serves, in connection with the float valve, to maintain a constant level of liquid fuel within the float chamber 12. A drain cock 25 may be tapped into the bottom wall of the float chamber, if desired, in order to permit draining of the chamber for cleaning purposes or withdrawal of fuel for any purpose.

The lower open end of the body 10 of the carburetor is externally threaded to receive a threaded flange 26 of a substantially cup-shaped heater 27, a bottom forming plate 28 being clamped between the lower end of the body 10 and the heater 27 to form a removable closure for the lower end of the body. The peripheral wall of the heater 27 is perforated to receive binding posts 29 and a heating coil 30 of any suitable type is connected between these binding posts, being disposed within the body of the heater and below the bottom plate 28. Obviously, if suitable current is passed through the heating coil 30, the bottom plate 28 will be heated and any liquid fuel dropped, sprayed, splashed or otherwise deposited upon it will be converted into a relatively dry gas.

A transverse partition wall 31 extends across the body 10 of the carburetor in spaced relation to its lower end and with the body of the carburetor and the bottom plate 28 provides a gas generating chamber 32. This partition wall 31 is formed centrally with a relatively large opening to receive a cylindrical plug 33, the lower end of which is preferably beveled, as shown. This plug 33 is formed with an annular flange 34 engaging against the lower face of the partition wall 31 and a nut 35 threaded about the upper portion of the plug and engaging the partition wall holds the plug in place. This plug is formed with a chamber 36 which opens through its lower end to provide a frusto-conical valve seat 37 and which, at its upper end, opens into a tubular extension 38 which projects to a level somewhat above the liquid fuel level in the float chamber 12. A plurality of radial passages 39 communicate with the chamber 36 of the plug and with a passage 40 extending from the lower portion of the float chamber 12 through the web 13 and into the partition wall 31, as shown in Fig. 2.

The upper open end of the carburetor body 10 is closed by a cap plate 41 secured by screws or bolts 42 and the body immediately below its upper end is provided with a laterally directed outlet branch 43 adapted, as shown at 44, for connection with the intake manifold of an engine. Disposed against the inner face of the cap plate 41 is the disk-shaped body 45 of the throttle valve 46. This throttle valve comprises the body 45 and depending arcuate flange 47

which engages against the inner face of the carburetor body and is movable to close the passage 43 to any desired extent through turning of the body 45. The body portion 5 of the throttle valve is formed centrally with an opening surrounded by an unstanding flange 48 which seats in the opening in the top plate 41 and serves to centralize the throttle valve. Above the top plate, this 10 flange is reduced and formed with angular faces 49 to lockingly receive the intermediate portion of a throttle valve lever 50 and above these angular faces is further reduced and screw threaded, as shown at 51, to receive a nut 52 by means of which the throttle valve is held against vertical movement. The throttle valve lever 50, as clearly shown in Fig. 1 and Fig 5 is so proportioned and mounted upon the stem portion of the throttle 20 valve as to extend diametrically across the top of the carburetor and has one arm directed upwardly and outwardly, as shown at 53, to receive a link by means of which it may be connected to any suitable throttle 25 valve controlling mechanism, such as the hand lever on a steering wheel or foot pedal.

An adjusting screw 54 having a milled or knurled head 55 is threaded through the opening of the throttle valve body 45 and is 30 formed with an axial chamber or socket 56 extending to the head and with an opening 57 formed through the head. A needle valve 58 co-acts with the valve seat 37 and its stem 59 extends through the sleeve 38 35 and through the chamber and opening of the adjusting screw 54. A helical spring 60 surrounds this stem and is located within the chamber of the adjusting screw, bearing at its upper end against the head of the 40 screw and at its lower end against a collar 61 adjustably secured upon the stem by a set screw 62. As will be apparent, this spring normally tends to hold the fuel supply valve 58 in closed position to prevent 45 passage of fuel from the float chamber 12 into the gas generating chamber 32.

The upper end of the valve stem 59 is bent outwardly and downwardly, as shown at 63, and then outwardly in parallel spaced 50 relation to the top plate 41, as shown at 64, to provide a cam engaging arm and the terminal of the valve stem as directed downwardly, as shown at 65, to seat in an opening 66 formed through the cap plate and the 55 flange of the carburetor body to which the plate is connected. By this means, the valve stem is held against turning movement, but is free for vertical movement to open and close the valve. A substantially 60 semiannular cam plate 67 has one end riveted or otherwise secured to the throttle valve lever at a point intermediate the connection of the lever with the throttle valve stem and the upwardly directed terminal of the lever 65 and its opposite end is formed with a

threaded opening to receive an adjusting screw 68 having a milled head by means of which it may be readily turned. That end of the cam plate receiving the adjusting screw 68 extends above the opposite end of 70 the throttle valve lever and the end of the shank of the screw engages the throttle valve lever. The cam plate 67 is formed of resilient metal and by proper manipulation of the adjusting screw 68, the end carrying 75 such screw may be sprung upwardly to a more or less extent, as desired. The lateral arm 64 of the needle valve stem 59 engages the upper face of this cam plate and, as a result, the needle valve will be opened or 80 closed during turning of the throttle valve lever to an extent dependent upon the setting of the cam plate and the amount of turning of the lever. The cam plate inclines gradually upward from its fixed to its free end, 85 but adjacent its fixed end is formed or bent to provide a more abrupt incline, as shown at 69, to insure a rapid partial opening of the needle valve upon the first turning of the throttle valve and lever to open the throttle 90 valve.

The movement of the throttle valve in one direction is adjustably limited by means of a stop screw 70 threaded through an upstanding lug 71 formed upon the cap plate 95 41 and adapted to engage one end portion of the throttle valve lever when the throttle valve is closed. The movement of the valve in the opposite direction is correspondingly limited by a second stop screw 72 threaded 100 through the same lug, extending at right angles to the first and adapted to engage the opposite end of the throttle valve lever when the throttle valve is fully opened. The carburetor body 10, immediately above its transverse partition wall 31 and preferably at a point diametrically opposite the float chamber, is formed with an air inlet passage 73 surrounded by a threaded annular flange 74 adapted to receive a perforated cap 75 in 110 order that air admitted to the carburetor may be strained and freed of impurities. Immediately above this air inlet passage, the carburetor body is formed with an inwardly directed annular flange providing a 115 valve seat 76 and above this valve seat, the body is flared to provide an annular valve chamber 77. A disk-shaped valve 78 engages the seat 76 and is formed centrally with a relatively large opening 79 through 120 which the sleeve 38 projects. A helical spring 80 engages between the upper face of this valve 78 and the lower end of the adjusting screw 54 and serves to normally hold the valve against its seat, the tension of this 125 spring being readily adjusted by means of the screw 54. This spring preferably tapers in diameter from its lower to its upper end in order that its lower end may be large enough to engage the valve adjacent its pe- 130

2
ripheral edge and so hold it against tilting movement. A pipe 81 projects at one end into the intermediate portion of the gas generating chamber 32 and at its upper end 5 projects upwardly into the outlet branch or passage 43 of the carbureter, terminating substantially midway of this passage and being formed with a frusto-conical valve seat 82 at its end. A needle valve 83 has its 10 valve stem 84 threaded through the upper wall of the outlet branch 43 in such a manner that the valve 83 may be adjusted to permit passage of any desired amount of gas from the pipe 81 into the passage 43. The 15 outer end of the valve stem 84 is provided with a peripherally notched adjusting head 85 and a resilient pawl 86 mounted upon the carbureter engages in one or another of the notches of this head to hold the valve 83 20 in adjusted position.

When describing the operation, I will assume that the carbureter is connected to the usual intake manifold of an internal combustion engine and that a liquid fuel supply pipe is properly connected to the nipple 18. I will also assume that the heating coil 30 is in circuit with any suitable source of current, such as a generator or storage battery. Under these circumstances, the throttle valve lever is swung to slightly open the throttle valve and the fuel valve 58 and the bottom plate 28 is heated by closing the circuit through the coil 30. Kerosene or other liquid fuel will then pass from the 25 float chamber 12 through the passage 40 and past the valve 58 and drop upon the heated plate 28. This fuel will then be converted, while still in the chamber 32, into a gas and, as a gas, will pass through the pipe 35 81 into the passage 43. The meeting air and gas will, therefore, combine in the passage 43 and pass through the manifold into the various engine cylinders.

When the engine has been properly started, it may be speeded up to any desired amount by further opening of the throttle valve to admit more air and also to admit more fuel into the gas generating chamber 32. It should be noted that the amount of 40 air supplied is dependent upon the suction of the engine, although it may be regulated by means of the adjusting screw 54. It should also be noted that the quantity of fuel supplied to the gas generating chamber 50 32 is independent of the engine suction being dependent solely upon the setting of the cam plate 67 and the extent to which the throttle valve is opened. The valve 83 is adjusted only to adapt the carbureter to 55 the particular type or size of engine with which it is employed and after having been once properly set for a given engine remains unchanged. The float valve 23 is necessary to insure a uniform feeding of liquid fuel

to the chamber 32 for any given setting of 65 the valve 58 as without this float valve, the pressure of liquid fuel would vary according to the pressure on the fuel in the supply tank or the depth of fuel therein, dependent upon whether a pressure or gravity 70 feed tank was employed and these variations in liquid pressure would result in a more or less rapid flow of fuel past the valve 58.

By forming the cam plate 67 properly and 75 by adjustment of its setting screw 68, a proper supply of liquid fuel to the carbureter may be insured at all engine speeds. The sleeve 38 extending above the liquid 80 level in the float chamber prevents any escape of fuel, due to leakage about the valve stem 59.

It will be obvious that any desired means 85 for heating the fuel supplied to the chamber 32 may be employed without in the slightest degree departing from the spirit of my invention. For instance, a heater of the type shown in Fig. 6 will probably be found most practicable upon the engines of some 90 motor vehicles because of its saving of electric current. This form of heater, shown at 95 87, is identical with that previously described, with the exception that a pipe 88 is passed diametrically through the lower portion of the body of the heater and adapted to be connected to a pipe, not shown, leading from any suitable source of hot air supply, such as a heating jacket about the exhaust 100 manifold of the engine. With this type of heater in use, the gas generating chamber 105 will be initially heated by passing a current through the heating coil and after the engine has become heated, the hot air furnished to the pipe 88 will be sufficient to carry on the gas generation and the electric 110 current may be cut off.

In Fig. 7 I have illustrated a form of heater which is particularly adapted for use 115 upon stationary engines in which the body 89 of the heater is increased in length and formed about its upper portion with a plurality of draft openings 90 and at one side, with a relatively large opening 91. Within the body of the heater is disposed a liquid fuel lamp or burner 92 having a wick or 120 burner proper 93 and a filling spout 94. This burner is removable from the heater and may be readily filled by applying its filling spout 94 to the drain cock 25 of the carbureter.

Having thus described the invention, what is claimed as new is:

1. A carbureter including a body providing a float chamber, a gas generating chamber, and an outlet passage, a float valve 125 adapted to maintain a constant fuel level in the float chamber, means for supplying liquid fuel from the float chamber to the gas

generating chamber including a fuel valve, means for leading gas from the gas chamber to the outlet passage, and means for supplying primary air to the outlet passage at a 5 point behind the point of gas admission said latter means including an air valve, and a manually operable throttle valve interposed between the air valve and passage, the said second mentioned means entering the outlet 10 passage beyond the manually operable air throttle valve.

2. In a carbureter, a body providing a float chamber, an air passage and a gas generating chamber open at its lower end, communicating means between the float chamber and gas generating chamber, communicating means between the gas generating chamber and outlet passage, means for supplying air to the outlet passage, a false bottom closing 15 the lower end of the gas generating chamber, and a heater engaged directly on the carbureter body and holding the false bottom in place, said heater including a hollow body providing with the false bottom a chamber 20 below the gas generating chamber and inclosing means for heating the false bottom, said means including an electrical heating coil and a pipe leading through the heater and adapted for communicative attachment 25 with a source of hot air supply, the pipe being independent of the heater.

3. In a carbureter, a body providing a float chamber, a gas generating chamber and an outlet passage, the generating chamber 30 and passage being separated by a partition web formed with an annular chamber in communication with the float chamber and with a bore centrally of the annular chamber, a valve seat forming plug threaded into 35 the bore and closing it and formed with a chamber and passages establishing communication between the chamber and the annular chamber, a valve operating in the plug and controlling passage of fuel from the chamber 40 therein to the gas generating chamber, an air throttle valve controlling passage of air to the air passage, and operative connection 45 between the valves.

4. In a carbureter, a body providing an 50 outlet passage adjacent its upper end, an air inlet passage intermediate its length, a fuel vapor chamber at its lower end, and a float chamber, means for maintaining a constant fuel level in the float chamber, a fuel 55 valve controlling supply of fuel from the float chamber to the fuel vapor chamber, an inlet from the fuel vapor chamber to the outlet passage, means controlling supply of air to the carbureter, means controlling the 60 opening of the fuel valve for governing the volume of flow through the said inlet into the outlet passage, and a throttle valve controlling the volume of air flowing from the carbureter through the outlet passage to pro-

vide with the fuel supply from the said inlet 65 a fuel mixture, the said throttle valve controlling means governing the opening of the fuel valve.

5. In a carbureter, a body providing an outlet passage and a float chamber, a partition within the body defining one wall of a gas generating chamber disposed at one side of the partition and closed from the outlet passage thereby, means for admitting air to the outlet passage at the opposite side of the 70 partition, a heater connected to the body and including a plate disposed to be normally heated and providing another wall of the said gas generating chamber opposite to the said partition, means mounted upon the 75 partition for discharging liquid fuel from the float chamber into the gas generating chamber, and means establishing communication between the gas generating chamber and the said outlet passage. 85

6. In a carbureter, a body providing a float chamber, an air passage and a gas generating chamber open at its lower end, communicating means between the float chamber and gas generating chamber, communicating 90 means between the gas generating chamber and air passage, means for supplying air to the air passage, a false bottom rested against the lower end of the gas generating chamber at the lower end of the body, and 95 a hollow heater formed at its upper end with an outwardly offset flange seating said false bottom upon the offset of the flange and threaded onto the lower end of the body for securing the false bottom in place. 100

7. In a carbureter, a body providing an outlet passage and a float chamber, a fuel valve controlling supply of fuel from the float chamber into the body and continued at its upper extremity to form an arm operatively engaged with the body for holding the valve against rotation but permitting vertical movement of the valve, a throttle valve controlling discharge of air through said passage, and means controlled by the 105 throttle valve and coacting with said arm for opening the fuel valve coincident with the opening of the throttle valve. 110

8. In a carbureter, a body providing an outlet passage and a float chamber, a plate 115 closing the body at its upper end, a fuel valve controlling supply of fuel from the float chamber into the body and continued at its upper extremity to form a rebent portion having a downwardly directed terminal slidably engaged through said plate for holding the valve against rotation but permitting vertical movement of the valve, a throttle valve controlling discharge of air through said passage, and means controlled 120 by the throttle valve and coacting with said arm for opening the throttle valve coincident with the opening of the fuel valve. 125

9. In a carbureter, a body providing a float chamber, a gas generating chamber and an outlet passage, a partition closing the gas generator chamber from the outlet passage, means for supplying liquid fuel from the float chamber into the gas generating chamber through the partition, means for supplying primary air to the outlet passage, a valve at the entrance of the outlet passage for controlling air discharge therethrough, and means for leading gas from the gas generating chamber around the partition to the outlet passage at a point beyond that of primary air admission and beyond said valve in constantly open communication with the discharge end of said passage.
10. In a carbureter, a body providing a float chamber, a gas generating chamber and

an outlet passage, a partition closing the gas generating chamber from the outlet passage, means for supplying liquid fuel from the float chamber to the gas generating chamber through said partition, means for supplying primary air to the outlet passage, a conduit for leading gas from the gas generating chamber around the partition to the outlet passage at a point beyond that of primary air admission and in constantly open communication with the discharge end of the outlet passage, and a valve adjustable 30 independently axially of said conduit to control the flow of gas through the outlet passage.

In testimony whereof I affix my signature.

LEROY V. BERKEBILE. [L. S.]
